By

Attorney

Albert F. Robinson

UNITED STATES PATENT OFFICE

HOMER HERBERT VAN HAGAN, OF BUFFALO, NEW YORK, ASSIGNOR, BY MESNE ASSIGNMENTS, TO CERTAIN-TEED PRODUCTS CORPORATION, A CORPORATION OF MARYLAND

COMPOSITE BOARD

Application filed January 28, 1927. Serial No. 164,273.

This invention relates to composite boards and aims to provide a novel and improved board of the type which is characterized by its superior durability.

5 The nature of the invention may be readily understood by reference to one illustrative embodiment thereof shown in the accompanying drawing in which:—

10 Fig. 1 is a fragmentary view, partly in section, showing a means for applying toughening material adjacent the margins of composite boards.

Fig. 2 is a right hand side view of Fig. 1.

15 The illustrative composite board is typified herein by a plasterboard comprising a body of plaster or the like having covering material of paper adhering to the faces thereof, and adhesively reenforcing the plaster body from edge to edge. The margins 20 of one or both cover sheets may be manipulated in such a way as to cover also the side edges of the plaster body. In the present board, the margins of the bottom sheet are folded over the edges of the plaster body and 25 adhere thereto.

A board of this character may advantageously be made by what is known as the continuous process, namely a process where- 30 in a quantity of plaster is deposited upon a continuously travelling cover sheet (in this instance the bottom cover sheet) and there- after uniformly spread over the sheet to uniform depth, the top cover sheet being 35 preferably simultaneously applied during the spreading process. During the process of forming the board, the margins of the cover sheet are advantageously manipulated to cover the edge of the board.

40 The board is thus made in a continuous strip or sheet which is cut into suitable lengths as soon as the plaster has become sufficiently hard or set to permit the board to be handled.

45 After the boards have been cut to length, they are generally dried to remove excess moisture.

During the stage of manufacture after the formation of the product, but before the board has been cut to length, the product 50 is suitably treated to toughen it, adjacent its

edges. In the present instance, the product is treated to toughen it superficially at its side edges and throughout a narrow region adjacent such side edges. This superficial toughening may be conveniently effected by 55 the application of glue or shellac or other material which will protect or toughen the paper against abrasion or peeling.

The board strip comprises a plaster body 1 contained between cover sheets 2 and 3 and 60 which is fabricated and conveyed on endless conveyor 4. Margins 5 and 6 of sheet 2 are folded towards the other sheet to inclose or partially inclose the edges of the plaster body.

65 Means for applying the toughening material are represented by wicks 10 which drag along the side edges of the board and overlap as much of the surface of the board as it is desired to treat. The wicks may be supplied from a suitable source of supply typified by the receptacles 7 which are provided with conduits 8 that conduct the coating material to the wicks. Valves 9 may advantageously be provided in the conduits to regulate the supply of coating material to the 70 wicks. The capillarity of the wicks serves to conduct the material to the product.

75 The vehicle used for carrying the coating substance depends upon the character of substance applied. If glue be used water 80 will serve as a satisfactory vehicle.

85 By the foregoing described means the continuous strip or sheet of board is treated as it passes from the forming mechanism to the point where it is severed into boards of proper length.

90 The toughening of the edges of the board serves to prevent scuffing or scratching of the paper which occurs during the ordinary handling of the board and particularly where the product is slightly moist. In such condition the paper is particularly susceptible to scuffing and peeling. Even with the repeated handling to which the board is subjected before it is received by the retailer or material 95 man, the board with the toughened edges always presents a neat appearance, thus promoting the sale of the product.

99 In the illustrative board, the bottom sheet of paper generally serves as the face side or

sheet of the board, that is, the face which receives the wall paper or other decoration. Generally in the handling of this type of board unusual care is taken to preserve the face side of the board from any marring or any other damage, and it is, therefore, unnecessary to apply any of said coating material to this face of the board. It is sufficient to coat simply the edges of the board, and, 10 the region at the back of the board adjacent the edges. With other boards of this type the face sheet has been specially treated in its manufacture to give a surface which will readily receive paint or other decoration, but 15 which will resist any penetration or absorption of paint into the body of the paper. Paper so treated does not generally require the protective coating given the edges of the board.

20 Obviously the invention is not limited to the details of the illustrative product and method above described, since these may be variously modified. Moreover, it is not indispensable that all the features of the invention be used conjointly, since certain features may be advantageously employed in 25 various combinations.

Having described one embodiment of my invention, I claim:

- 30 1. A composite board comprising a body material and cover sheets for facing said body material, one of the sheets folded over the edges of the body material, and toughening material applied to the folded edges and along the margins of the other cover sheet.
- 35 2. A composite board comprising a body material and facing sheets, a strip integral with one of said sheets extending along the edges of the body material and a coating applied to the exterior surface of the strip to prevent peeling.
- 40 3. A composite board comprising a body material and facing sheets, a fibrous strip integral with one of said sheets extending along the edges of the body material, and toughening material applied to the exterior surface of the fibrous strip.
- 45 4. A composite board comprising a body material and facing sheets therefor, a fibrous strip integrally attached to one of said facing sheets and extending along the edges of the body material, and toughening material applied to the exposed surface of the strip to prevent peeling.
- 50 5. A composite board comprising a body material and cover sheets therefor, the margins of at least one cover sheet being folded over the edges of the body material, and toughening material applied along the margins of the cover sheets.

In testimony whereof, I affix my signature.
HOMER HERBERT VAN HAGAN.
